UNITED STATES PATENT OFFICE.

LOUIS JOHN LE MESURIER, OF NEWCASTLE-UPON-TYNE, ENGLAND, ASSIGNOR OF ONE-HALF TO SIR W. G. ARMSTRONG WHITWORTH & COMPANY LIMITED, OF NEWCASTLE-UPON-TYNE, ENGLAND.

AIRPLANE-LAUNCHING APPARATUS.

1,347,105.

Specification of Letters Patent. Patented July 20, 1920.

Application filed May 5, 1920. Serial No. 379,120.

To all whom it may concern:

Be it known that I, LOUIS JOHN LE MESURIER, a subject of the King of England, residing at Newcastle-upon-Tyne, Northumberland, England, have invented certain new and useful Improvements in Airplane-Launching Apparatus, of which the following is a specification.

This invention relates to apparatus for launching an aeroplane or seaplane from a ship's deck or like restricted area where the flying speed must be obtained within a short distance. The object of this invention is to provide a launching apparatus which has fewer parts of less weight than those previously proposed and which is of simple operation and as compact as possible.

According to this invention the apparatus comprises a track on which a carriage 20 is adapted to travel, this carriage either bearing the entire weight of the aircraft to be launched in the case of a seaplane but merely exerting the necessary accelerating force in the case of an aeroplane the wheels 25 of which travel on the track. The accelerating force is transmitted to the carriage through a steel wire rope one end of which is secured to the fore part of the carriage and a similar rope also connected to the carriage effects retardation, the two ropes together with the carriage forming a complete chain whose extreme ends are anchored to opposite ends of the track or some fixed portion of the main structure and 30 which pass over pulleys capable of being moved parallel to the track by the reciprocation under compressed air of a piston within a working cylinder. In addition to the working cylinder which imparts acceleration to the carriage a second retarding and returning cylinder is provided and a valve gear is arranged actuated by the pressures which obtain within these cylinders in such a way that the exhaust ports of the cylinder 45 in which the greatest pressure exists are closed while those of the other cylinder are opened. In this way during launching or acceleration the exhaust ports of the retarding cylinder are open and during retardation or return of the carriage to its original position the exhaust ports of the working cylinder are open and those of the returning cylinder closed. The retarding cylinder is

preferably provided with a hydraulic buffer with or without the provision of a buffer 55 spring.

One construction of apparatus according to this invention is illustrated by way of example in the accompanying drawings in 60

Figure 1 is a sectional plan,

Fig. 2 an elevation, and

Fig. 3 a sectional plan, on an enlarged scale, showing the valve mechanism.

The apparatus comprises a track or plat- 65 form A along which is adapted to travel a carriage B which either bodily supports a seaplane B' or exerts the necessary accelerating force for an aeroplane whose wheels travel upon the track A. Secured to a for- 70 ward end of the carriage B is a steel wire rope C, a similar rope D being connected to the rear end of the carriage and these ropes together with the carriage B forming a complete chain, whose extreme ends are 75 anchored to the opposite ends of the track or fixed structure after passing around a fixed vertical pulley C' D' near each end of the track and two movable horizontal pulleys. This rope system runs from the end 80 of the rope D anchored to the rear portion A' of the track around a movable horizontal pulley D² back and over a fixed vertical pulley D' above the anchored end to the rear end of the carriage B and from the fore end 85 of the carriage (in the form of the rope C) over a fixed vertical pulley C' near the launching end track around the second mov- 90 able horizontal pulley C² to the forward end A² of the track where the other end of the rope C is anchored.

Travel of the carriage is obtained by moving the horizontal pulleys C² D² in one direction or the other relatively and parallel to the track. To this end a working cylinder E containing a piston F supplied with compressed air through a suitable firing valve E' is provided, the piston F being connected by a rope G to the forward horizontal pulley C² the ratio being such that when the piston reciprocates within its cylinder, the horizontal pulley C² is drawn toward the rear end A' of the platform, thus exerting a pull on the launching rope C. In the same way the rear movable horizontal pulley D² is connected to the piston H of a sec- 100 105

ond returning or retarding cylinder J by a rope K and the travel of each piston is equal to half that of the carriage.

Communicating with each cylinder is a valve chamber L provided with exhaust ports L' L² and containing an exhaust valve M of the piston type. Exhaust from the cylinder E after launching has been effected takes place as soon as ports E² formed in its 10 length are uncovered by the working piston F. During the return movement of the piston F however, exhaust takes place through the piston valve M which also controls the exhaust ports H' of the return cylinder. 15 The piston valve M is actuated by pressure in such a way that when the working cylinder E is launching, then the exhaust ports H' of the return cylinder are open and vice versa when the return cylinder J is operating to restore the parts to their initial 20 position, then the ports of the working cylinder are open.

As soon as the aeroplane has been launched from the carriage the latter is brought to 25 rest by the piston H of the return cylinder J engaging the hydraulic buffer piston N which is conveniently of the usual type and may in addition have a buffer spring O if desired. Shock is prevented by so arranging 30 the exhaust ports as to trap or cushion the column of air between the return piston H and the piston N of the hydraulic buffer. Compressed air to actuate the return piston in order to restore the parts to their initial 35 position is supplied through a pipe P and controlled stop valve P'.

It is to be understood that although the term "air plane" is used in the following 40 claims this covers both seaplanes and aeroplanes, and that the details of construction can be considerably modified without departing from this invention.

What I claim as my invention and desire to secure by Letters Patent is:—

45 1. In apparatus for launching an air plane from a restricted area, the combination of a track, a carriage adapted to travel thereon, an accelerating rope connected to the carriage, a retarding rope also connected thereto, said ropes constituting with the carriage a single chain having its ends anchored, pulleys near each end of the track over which said chain passes and means for moving the pulleys in either direction parallel to the length of the track to impart acceleration or retardation to the carriage.

50 2. In apparatus for launching an air plane from a restricted area, the combination of a track, a carriage adapted to travel thereon, an accelerating rope connected to the carriage, a retarding rope also connected thereto, said ropes constituting with the carriage a single chain having its ends anchored, a cylinder, a piston adapted to impart 55 acceleration to the carriage mounted to

reciprocate therein, a pulley connected to said piston over which passes the accelerating rope, a second cylinder, a retarding piston mounted to reciprocate therein and a second pulley connected to the retarding piston 70 over which passes the retarding rope.

3. In apparatus for launching an air plane from a restricted area, the combination of a track, a carriage adapted to travel thereon, an accelerating rope connected to the carriage, a retarding rope also connected thereto, said ropes constituting with the carriage a single chain having its ends anchored, a cylinder, a piston adapted to impart acceleration to the carriage mounted to 75 reciprocate therein, a pulley connected to said piston over which passes the accelerating rope, a second cylinder, a retarding piston mounted to reciprocate therein, a second pulley connected to the retarding piston over 80 which passes the retarding rope and means for controlling the supply of fluid pressure to the cylinders.

4. In apparatus for launching an air plane from a restricted area, the combination of a track, a carriage adapted to travel thereon, an accelerating rope connected to the carriage, a retarding rope also connected thereto, said ropes constituting with the carriage a single chain having its ends anchored, a cylinder having exhaust ports, a piston adapted to impart acceleration to the carriage mounted to reciprocate therein, a pulley connected to said piston over which 90 passes the accelerating rope, a second cylinder having exhaust ports, a retarding piston mounted to reciprocate therein, a second pulley connected to the retarding piston over which passes the retarding rope and valve mechanism controlling the flow of fluid 95 pressure to and from the cylinders so that the exhaust ports of the retarding cylinder are automatically opened during acceleration and similarly closed during retardation 100 the exhaust ports of the accelerating cylinder are opened.

5. In apparatus for launching an air plane from a restricted area, the combination of a track, a carriage adapted to travel thereon, an accelerating rope connected to the carriage, a retarding rope also connected thereto, said ropes constituting with the carriage a single chain having its ends anchored, a cylinder having exhaust ports, a piston adapted to impart acceleration to the 110 carriage mounted to reciprocate therein, a pulley connected to said piston over which passes the accelerating rope, a second cylinder having exhaust ports, a retarding piston mounted to reciprocate therein, a second pulley connected to the retarding piston over 115 which passes the retarding rope and valve gear comprising a cylinder, a piston actuated by the pressure within the accelerating 120 and retarding cylinders adapted to close the 125 130

exhaust ports of that cylinder in which the greatest pressure exists and simultaneously to open the exhaust ports of the other cylinder where the pressure is lowest.

- 5 6. In apparatus for launching an air plane from a restricted area, the combination of a track, a carriage adapted to travel thereon, an accelerating rope connected to the carriage, a retarding rope connected thereto, said ropes constituting with the carriage a single chain having its ends anchored to the opposite ends of the track, a working cylinder, an accelerating piston adapted to reciprocate therein, a pulley connected to said piston over which pulley passes the accelerating rope, a second cylinder, a retarding and returning piston mounted to reciprocate therein, a pulley connected to said piston over which passes 15 the retarding rope, means for reciprocating the pistons within their cylinders so as to move the pulleys parallel to the length of the track for the purpose described and a buffer adapted to cushion the movements 20 of the pistons at the ends of their stroke.
7. In apparatus for launching an air plane from a restricted area, the combination of a track, a carriage adapted to travel thereon, a cylinder, a piston therein adapted to impart acceleration to the carriage, a flexible connection between said piston and the carriage, a second cylinder, a retarding piston therein, and a flexible connection between 30 said retarding piston and the carriage.
- 35 8. In apparatus for launching an air plane from a restricted area, the combination of a track, a carriage adapted to travel thereon, a cylinder having exhaust ports, a piston therein adapted to impart acceleration 40 to the carriage, a flexible connection between said piston and the carriage, a second cylinder having exhaust ports, a retarding piston therein, a flexible connection between said retarding piston and the carriage and 45 valve mechanism between the two cylinders whereby the exhaust ports of the retarding

cylinder are automatically opened during acceleration and similarly closed during retardation and return when the exhaust ports of the accelerating cylinder open.

50 9. In apparatus for launching an air plane from a restricted area, the combination of a track, a carriage adapted to travel thereon, a cylinder having exhaust ports, a piston therein adapted to impart acceleration to 55 the carriage, a flexible connection between said piston and the carriage, a second cylinder having exhaust ports, a retarding piston therein, a flexible connection between said retarding piston and the carriage and 60 a valve gear comprising a cylinder, a piston actuated by the pressure within the accelerating and retarding cylinders in such a manner as to close the exhaust ports of that cylinder in which the greatest pressure exists and open those of the other cylinder 65 where the pressure is lowest.

10. In apparatus for launching an air plane from a restricted area, the combination of a track, a carriage adapted to travel 70 thereon, an accelerating rope connected to the carriage, a retarding rope connected thereto, said ropes constituting with the carriage a single chain having its ends anchored to the opposite ends of the track, a 75 working cylinder, an accelerating piston adapted to reciprocate therein, a pulley connected to said piston over which pulley passes the accelerating rope, a second cylinder, a retarding and returning piston 80 mounted to reciprocate therein, a pulley mounted to reciprocate therein, a pulley connected to said piston over which passes the retarding rope, means for reciprocating the pistons within their cylinders so as to move the pulleys parallel to the length of 85 the track for the purpose described and means for cushioning the movements of the pistons at the ends of their stroke.

In testimony whereof I have signed my name to this specification.

LOUIS JOHN LE MESURIER.
